US00D831203S

(12) **United States Design Patent** (10) **Patent No.:** **US D831,203 S**
(45) **Date of Patent:** **** Oct. 16, 2018**

(54) **ENTERAL SYRINGE**(71) Applicant: **NEOMED, INC.**, Woodstock, GA (US)(72) Inventors: **Benjamin M. Davis**, Woodstock, GA (US); **Aaron N. Ingram**, Canton, GA (US); **John Burke**, County Roscommon (IE); **Mark M. Costello**, County Mayo (IE)(73) Assignee: **NEOMED, INC.**, Woodstock, GA (US)(**) Term: **15 Years**(21) Appl. No.: **29/530,724**(22) Filed: **Jun. 18, 2015****Related U.S. Application Data**

(63) Continuation-in-part of application No. 29/519,107, filed on Mar. 2, 2015, now Pat. No. Des. 807,502.

(51) **LOC (11) Cl.** ..... **24-02**(52) **U.S. Cl.**USPC ..... **D24/130**(58) **Field of Classification Search**

Primary Examiner — David Muller*Assistant Examiner* — Nathan Johnston(74) *Attorney, Agent, or Firm* — Gardner Groff Greenwald & Villanueva, PC(57) **CLAIM**

The ornamental design for an enteral syringe, substantially as shown and described.

DESCRIPTION

FIG. 1 is a perspective view of an enteral syringe showing our new design.

FIG. 2 is a front elevation view thereof.

FIG. 3 is a rear elevation view thereof.

FIG. 4 is a first side elevation view thereof.

FIG. 5 is a second side elevation view thereof.

FIG. 6 is a first end elevation view thereof; and,

FIG. 7 is a second end elevation view thereof.

The broken lines show portions of the design that form no part of the claimed.

1 Claim, 4 Drawing Sheets# US D831,203 S
